(57) **CLAIM**

The ornamental design for a dripless hose bib, as shown and described.

DESCRIPTION

FIG. 1 is a top plan view of the novel dripless hose bib having a female inlet port;

FIG. 2 is a bottom view thereof;

FIG. 3 is a left side elevation view thereof and the right side elevation view is identical but reversed;

FIG. 4 is a front elevation view thereof;

FIG. 5 is a rear elevation view thereof;

FIG. 6 is a top plan view of a first alternative embodiment of the novel dripless hose bib having a male inlet port;

FIG. 7 is a bottom plan view thereof;

FIG. 8 is a left side elevation view thereof and the right side elevation view is identical but reversed; and,

FIG. 9 is a rear elevation view thereof and the front elevation view of the first alternative embodiment would be the same as that illustrated in FIG. 4.
